UNITED STATES PATENT OFFICE

90,818

DESIGN FOR AN IMPRESSED TEXTILE FABRIC

Benjamin Salzberg, New York, N. Y.

Application July 27, 1933. Serial No. 48,841

Term of patent 3½ years

To all whom it may concern:

Be it known that I, BENJAMIN SALZBERG, a citizen of the United States, residing at 575-8th Avenue, in the city, county and State of New York, have invented a new, original, and ornamental Design for an Impressed Textile Fabric, of which the following is a specification, reference being had to the accompanying drawing, forming part thereof.

The figure is a plan view of a piece of textile fabric, showing a repeat unit of my new design.

The characteristic feature of my design resides in the shiny and polished appearance of the depressed elements of the textile fabric.

I claim:

The ornamental design for an impressed textile fabric as shown and described.

BENJAMIN SALZBERG.
